UNITED STATES PATENT OFFICE.

GEORGE W. MASCORD, OF LONDON, ENGLAND.

GEARING.

No. 872,528.

Specification of Letters Patent.

Patented Dec. 3, 1907.

Application filed January 9, 1905. Serial No. 240,267.

To all whom it may concern:

Be it known that I, GEORGE WILLIAM MASCORD, a subject of the King of Great Britain and Ireland, residing at 5 The Crescent, 5 Church Road, Barnes, London, England, have invented certain new and useful Improvements in Gearing, of which the following is a specification.

This invention relates to the application 10 and distribution of motive power particularly for use in starting machinery and for such and similar purposes, where electro-motors are employed as the source of motive power and where a powerful starting effort is 15 required.

The invention is of special utility in its application to electric plants for driving rotary printing presses, and in fact generally in cases where there is a great starting torque, 20 and the invention has for its object to avoid heavy draft on the main current at starting, and to provide effective means for bringing up the speed of the press or machine, while the main driving electro-motor is rotating at 25 constant speed.

According to the invention in its application to a rotary web newspaper printing press driven by means of an electro-motor, a friction clutch is interposed between the motor 30 and the machine, and the motor shaft is connected to the machine shaft by reducing gear, by which the machine shaft may be rotated at a relatively slow speed and under full power of the electro-motor, whereby the 35 inertia at starting may be effectively overcome without any undue drain upon the current circuit.

According to the invention also an auxiliary electro-motor or electro-motors may be 40 employed to operate the speed reducing gear by which the machine shaft or shafts may thus be caused to rotate at a relatively slow speed at starting.

In carrying the invention into effect according to one modification in its application to an electro-motor plant for driving a rotary web newspaper printing press, I may provide the motor shaft and the machine shaft in line and a friction clutch interposed for the purpose of disconnecting or connecting them together at will, and upon the motor shaft I provide a gear wheel or pulley for transmitting motion to a worm and worm wheel or other speed reducing gear which causes the 55 rotation of a spring controlled pawl and

ratchet device mounted upon a shaft upon which a bevel pinion or other gear may be provided gearing with corresponding bevel pinions mounted upon a counter-shaft, upon which also a pinion is mounted gearing with a spur wheel mounted upon the machine shaft, so that thus on starting, the friction clutch will be disconnected and motion will be conveyed through the worm and worm wheel gear by the spring pawl and ratchet or other similar device to the machine shaft, whereby the latter is caused to rotate slowly, and on a certain speed being attained by the machine shaft, the friction clutch is put into engagement, whereby the speed of the machine shaft is augmented and the pawls of the ratchet device will slip.

A clutch may be provided or a loose pulley or other suitable device for disconnecting the speed reducing gear on the friction clutch being put into operation.

The spring and ratchet device may advantageously consist of a disk or casing fixedly secured to the worm wheel aforesaid, carrying pawls having their rear extremities provided under the operation of springs to maintain them in contact with the cam or ratchet wheel. The latter is keyed upon the shaft, upon which the disk or casing aforesaid is loosely mounted, so that thus on the rotation of the worm wheel, the cam or ratchet wheel will be rotated and thus also the intermediate shaft which gears with the counter-shaft. Any other suitable gear may however be employed, which, while permitting of motion being communicated at reduced speed at starting, will permit of the speed of the machine being augmented, or of the machine being directly driven without the reducing gear being disconnected from the motor.

According to another modification an auxiliary motor or auxiliary motors may be used to cause the rotation of what may be designated as the worm shaft or two motors may be employed where the main motor is used for driving two presses or two parts of a press, one on each side of the motor.

The friction clutch may be so provided as while being put into operation it will cause the disengagement of the clutch controlling the speed reducing gear, or instead the respective clutches may be juxtaposed to be operated by the same lever, or instead of an ordinary clutch being provided for the con-

- trol of the speed reducing gear, a friction clutch may be employed, or the clutches may be operated by means of a solenoid whose circuits may be under the control of switches 5 suitably provided, or a compressed air cylinder and piston and valve or any other means may be used for the same purpose so that thus the plant may be under control from a distant point.
- 10 According to another modification where two machines or two parts of the same machine are operated from a main motor disposed between them an auxiliary motor plant and reducing gear may be provided for the 15 operation of the respective parts of the machine or the respective machine, as the case may be, in which event only one counter-shaft may be employed for each auxiliary set, its rotation being caused by means of 20 worm and worm gear, the worm being mounted upon the auxiliary electro-motor spindle; a clutch being also provided upon each counter-shaft to put the auxiliary motor mechanism out of operation.
- 25 In the accompanying drawings, Figure 1 is an elevation showing the application of the invention to a rotary printing press, in which a pneumatic system supplements the hand control mechanism. Fig. 1^a is a diagrammatic view illustrating a system of pneumatic control. Fig. 2 is a diagrammatic detail elevation of a hydraulic system for supplementing the hand control mechanism. Fig. 3 is a diagrammatic detail elevation of 30 an electric system for supplementing the hand control mechanism. Fig. 4 illustrates a modification in which an auxiliary starting motor is employed. Fig. 4^a is a detail view of switch mechanism. Fig. 5 is a diagram 35 illustrating the electric connections with the main motor field and control, and Fig. 6 is a plan of a modified arrangement showing the application of the invention in the distribution of power to a number of separate machines or units as in a line shaft.

In Fig. 1 the invention is shown as applied to a rotary printing press formed in two parts, each part of the press being driven from an electro-motor m centrally disposed 50 between the two parts of the press or between the two presses, one only of which is shown in the figure, while the same gearing, except the controlling gear shown upon the left hand side of the press and hereinafter 55 more particularly described, is arranged upon the other side of the motor shaft for the second part of the press or for the second of the two presses. Such controlling gear need not be duplicated, as the two parts of the 60 presses may be coupled together by such means as the shaft m^{12} and the jaw coupling m^{13} thereon.

In Fig. 1 means are shown for putting the press into motion from the continuously running motor m , either by means of a hand le-

ver g or by pneumatic pressure. The hand lever g and the controlling piston h of the pneumatic cylinder h' is shown in the position assumed when the press is stopped or is ready for starting. The main motor shaft a 70 is shown provided with a clutch b which is preferably a friction clutch such as that known as the "Hele-Shaw" clutch, by which connection is effected with the shaft i provided with a gear wheel i' in gear with a 75 gear wheel j' upon the counter or driven shaft j which gear wheel i' transmits motion to the machine at normal speed. The motion to the press mechanism is transmitted through the gear wheel j^2 which meshes with 80 the gear wheel j' mounted upon the counter or driven shaft j . The slow moving shaft c is provided with a second clutch d which is advantageously of the jaw gripping type in which the engaged part d' is formed integral 85 with the gear wheel k which is freely mounted upon the slow motion shaft c and is set in position against the collar k' . This clutch d is operated by a tripping device by which it is released when the operating hand lever g 90 passes the position indicated at x , as hereinafter described.

The clutch d is engaged on the movement of the boss d^2 towards the clutch d , to which boss d^2 the toggle levers of the gripping jaws 95 are connected. The part d^3 of the clutch carrying the gripping jaws it will be understood is keyed to the slow motion shaft c . The main motor shaft a drives positively, without the intervention of a clutch, through 100 the countershaft l which is suitably carried in brackets which are not shown. Such shaft l may advantageously be geared with the main motor shaft a by means of the bevel pinions l' and l^2 and may communicate motion from the worm l^3 mounted upon it with a worm wheel l^4 which is loosely mounted upon the slow motion shaft c , and is provided with a number of pawls l^5 on its face 105 engaging with a boss l^6 fixed to the slow motion shaft c so that in the forward direction of movement of the worm wheel motion is communicated to the slow motion shaft c , but should the slow motion shaft c be moved at a greater velocity this is permitted by the 110 slipping of the pawls l^5 over the recesses or teeth provided upon the fixed boss l^6 .

Motion is communicated from the counter-shaft j through the shaft m^{12} to a complementary countershaft and similar gear upon 115 the other side of the machine or at the other side of the press.

The clutch operating gear consists of the hand control lever g pivoted upon the spindle g' and carrying upon same spindle g' a 120 toothed segment g^2 which gears with a rack g^3 mounted upon a rod g^4 at the extremity of which a piston h is connected which works within a cylinder h' whereby on air being admitted to one side of the piston h or the other,

the rack g and therefore the segment g^2 and the hand control lever g is moved in one direction or the other as required to increase or decrease the speed of the machine or to stop 5 the press: the admission and exhaust of air to and from the cylinder being conveniently effected by any suitable air valve such as the three-way valve h^2 which is connected up to the air supply pipe h^3 and which is in turn 10 connected with a receiver h^4 within which air may be maintained at a constant pressure by means of an air pump h^5 which is operated from an eccentric h^6 upon the main motor shaft a . The air pressure may be under the 15 control of a stop valve such as h^7 and may be led through pipes such as h^8 from an independent source or to the controlling mechanism of the second part of the press.

The boss d^2 of the clutch d is moved by the 20 bell crank lever n which is connected to a link n' , which is in turn connected to one arm of the bell crank lever n^2 , on the extremity of which weights n^3 depend, so that on the bell crank lever n^2 being tripped by the 25 movement of the operating lever g from the position indicated x , the weight n^3 would serve to retract the boss d^2 of the clutch d and thus disengage the freely mounted part d' and the pinion k .

30 On the movement of the operating lever g from the position indicated x , the bell crank lever n^2 will be tripped and will pass under the pawl n^4 . In this position the slow motion shaft c will be moving at its full speed, 35 and in this position also the clutch d will be slowly put into engagement, so that when the hand lever g reaches the position indicated y , the clutch b will be fully engaged so that the shaft i will rotate at the same speed 40 as the main motor shaft a . This operation is effected by means of a cam piece o mounted upon the pin g' of the hand control lever g . A groove is formed in the cam piece o within which a pin provided upon the bell crank 45 lever o^3 slides, and a link o^3 connects to the operating lever o^4 of the clutch b . After the operating hand lever g has reached the position indicated y , the pin will reach the segmental or dead part of the tail piece o' of the 50 cam, and no further movement will be given to the clutch operating the lever o^4 , which thus is held or locked in that position.

A connecting rod e may be connected to the lower extremity of the hand control lever 55 g , by which corresponding movements may be given to a second set of controlling apparatus provided upon the second part of the press or upon the second press, so that each press may be controlled together on the operation of one or other of the operating mechanisms.

60 A series of contacts p are provided, with which engage a contact piece n' provided upon the operating hand lever g , so that after 65 the operating hand lever g passes the position

indicated y , circuits may be closed by which the motor field may be weakened, and the speed thereby gradually accelerated.

Fig. 5 illustrates the connections of the switch with the controller and with the motor 70 field and mains. In Fig. 5 m is the main motor, m' the motor field, q q' are the mains, r is the controller, r' indicates the magnetic blow out therefor, and the contacts of the controller are numbered 1 to 10, of which 10 75 represents the normal full speed point. s is the field resistance box, and the shunt control contacts p are numbered 11 to 16 in sequence with the starter and controller r .

Fig. 2 illustrates a modified form of the 80 operating mechanism illustrated in Fig. 1 in which a hydraulic arrangement supplements the hand lever control mechanism, the plungers g^{41} being provided within hydraulic cylinders h^{11} which communicate through 85 pipes h^{12} with the cylindrical valve casings h^{13} in which the valves t t' slide, being connected together so as to be operable by the operating lever u , the valve cylinders being connected with the exhaust pipes t^2 and with 90 the supply pipes t^3 . In the position indicated pressure is supplied to the supply pipe h^{12} of the cylinder h^{11} to the right by which the hand control lever g is maintained in its resting position. When the operating lever 95 u is moved to the central position the pressure is sustained by each of the plungers g^{41} and the operating hand lever g is maintained in its central position, while when the operating lever u is to be maintained in its fur- 100thest position opposite to that in which it is illustrated in Fig. 2, full pressure is transmitted to the plunger on the left, whereby the hand control lever g is moved to its furthest position for full speed. 105

Fig. 4 shows a detail arrangement corresponding to Fig. 1 in which an auxiliary motor f is employed instead of gear communicating motion from the main shaft a .

Fig. 4^a illustrates a switch arrangement 110 for cutting out the auxiliary motor f upon the hand control lever g passing the position indicated x . This arrangement consists of a toothed segmental lever y , which is tripped by the hand control lever g in the manner 115 and substantially as the bell crank lever n^2 (Fig. 1); said lever being pivoted at y' and gearing with the toothed segment y^2 of the switch arm y^3 . A spring y^4 operates upon the passage of the hand control lever from 120 the position indicated x to restore the switch arm y^3 to open the switch and to cut out the auxiliary motor.

Fig. 3 illustrates an electric system for 125 supplementing the hand control mechanism in which solenoids g^{44} are connected to the rod g^4 , into the coils of which current is led from the supply mains q q' there being five sets of coils upon each of the solenoids connected to contacts numbered correspond- 130

ingly and respectively arranged upon each side of the controller v , so that in the movement of the controller v from the starting position indicated at x , the successive coils of the solenoid to the right are put into circuit whereby the solenoid is moved forward to the right and the operating hand control lever g is moved forward into the successive positions as hereinbefore described, while in 10 the movement of the hand lever of the controller v on to the contacts to the left in the opposite direction the coils of the solenoid g^4 to the left are put into circuit whereby the hand control lever is drawn to the left for 15 stopping the press.

Fig. 6 illustrates a modification of Fig. 1 in which the main motor shaft a is disposed at right angles to the machine shaft i and to the slow motion shaft c both of which latter 20 are parallel one to the other. In this case motion is communicated to the shaft i through the clutch b and through bevel pinions w one of which is mounted upon the motor shaft a and the other upon the part i'' 25 of the machine shaft i which part i'' it will be understood is thus positively geared and continuously rotates from the main motor shaft, while a worm l^3 upon the main motor shaft a gears with a worm wheel l^4 , which is loosely 30 mounted upon the slow motion shaft c and communicates movement to the said shaft through pawls l^5 and a fixed boss l^6 in substantially the same manner as hereinbefore 35 described, while a clutch d is provided upon the slow motion shaft c by means of which the movement from the slow motion shaft to the machine shaft i may be discontinued when the clutch b is set into operation to 40 drive the machine direct from the main motor shaft. The operation in this arrangement is substantially the same as that hereinbefore described.

In Fig. 1^a a diagram is illustrated of a pneumatic system of control applicable for 45 two presses or for two parts of a press in which both sets of control mechanism can be simultaneously controlled or only one and either from a general supply or from a special supply of compressed air. x is the general supply pipe branching off into the supply pipes x' leading to each set of control mechanism and to the respective valves h^2 . The special supply pipes x^2 connect with the branches of the general supply pipe x , while 50 the general and special supply pipes to each set are provided with stop valves x^3 , x^3 , x^4 , x^4 ; and the pipes x' may be connected and a stop valve x^5 provided thereon by which the special supply to either set of control mechanism 55 may be used for the other set also. The pipes connecting the valves h^2 to the

cylinders h' may also be connected together under the control of stop valves x^6 as illustrated.

What I claim as my invention and desire 65 to secure by Letters Patent is.

1. In combination, a motor shaft, a shaft in line therewith, a clutch interposed between, a driven shaft driving connections between it and said second shaft, a slow 70 speed shaft driven from said motor shaft, power transmitting means interposed between said slow speed shaft and the driven shaft, said transmitting means including a clutch, a trip lever and connections therefrom for operating said last named clutch, a lever and operating connections therefrom to the first named clutch, and means carried by said lever for operating the trip lever, substantially as described. 75

2. In combination, a motor shaft, a driven shaft, a slow speed shaft driven from the motor shaft, driving connections between the motor shaft and driven shaft, including a clutch, driving connections between the 80 slow speed shaft and driven shaft including a clutch, a lever and connected means for successively operating said clutches, and electrical means for moving said lever, substantially as described. 85

3. In combination, a motor shaft, a driven shaft, a slow speed shaft driven from the motor shaft, driving connections between the motor shaft and driven shaft, including a clutch, driving connections between the 90 slow speed shaft and driven shaft including a clutch, a bell crank lever connected to said first named clutch, a hand lever having a cam device for operating said bell crank lever, a bell crank lever and operating connections therefrom to said second clutch, and means carried by the said lever for tripping said bell crank lever, substantially as described. 100

4. In combination, a motor shaft, a driven 105 shaft, driving connections between the same, including a clutch, and a slow speed shaft, driving connections between the same and the motor shaft including a clutch, a lever, connections therefrom for successively controlling the said clutches, a segmental rack carried by said lever, a reciprocating rack engaging said segmental rack, and power means for operating said reciprocating rack, substantially as described. 110

In testimony whereof I have signed my name to this specification in the presence of two subscribing witnesses.

GEORGE W. MASCORD.
